WALTER G. BLACK AND AUGUST L. SEGELHORST, OF BREA, CALIFORNIA.

DEEP-WELL PUMP.

1,219,799.

Specification of Letters Patent.

Patented Mar. 20, 1917.

Application filed June 13, 1916. Serial No. 103,495.

To all whom it may concern:

Be it known that we, WALTER G. BLACK and AUGUST L. SEGELHORST, citizens of the United States, residing at Brea, in the county of Orange and State of California, have invented certain new and useful Improvements in Deep-Well Pumps, of which the following is a specification.

This invention relates to deep well pumps and the object of the invention is to provide novel means whereby the pump will be firmly supported within the tubing while in use and may be withdrawn from the well without necessitating a dismantling or without drawing of the tubing. Other incidental objects of the invention will appear as the description of the same proceeds.

The invention is illustrated in the accompanying drawings and its novel features will be particularly pointed out in the claims following the detailed description.

In the drawings just mentioned:

Figure 1 is a view showing the pump in elevation and the tubing and well casing in vertical section;

Fig. 2 is a view showing the plunger and cage with the connection between the plunger and the sucker rods in elevation and the pump barrel, the tubing and the casing in section.

Referring more particularly to the drawings, the numeral 1 designates the well casing and the numerals 2 and 3 indicate respectively the upper and lower sections of the tubing, while 4 indicates the pump barrel. In carrying out the present invention, the upper and lower sections of the tubing are connected by a coupling sleeve 5 having its ends internally threaded or otherwise constructed to be securely but removably connected to the adjacent ends of the sections of the tubing. The inner wall or bore of this coupling sleeve is flared or beveled, as indicated at 6, to provide a seat for an anchoring block which will be presently more particularly described. Below this flared or beveled seat 6, the lower end of the sleeve is flared downwardly and outwardly, as shown at 7, so as to permit expansion of the springs 8 secured to the shoe 9 and also to cause contraction of said springs when the pump barrel is being withdrawn. The pump barrel 4 is connected by a coupling 10 at its lower end to the shoe 9 and the said shoe is provided with longitudinal grooves 11 in its outer surface which receive leaf-

springs 8, the lower ends of the said springs being secured rigidly in the lower ends of the grooves while the upper ends of the springs play freely in the grooves as will be readily understood. The coupling 10 carries a cage 12 in which plays a ball valve to control the inlet of the fluid to the pump barrel. The upper end of the pump barrel is secured by threads, or any other preferred means, in the lower end of the anchoring block 13 which is adapted to seat in and bind upon the beveled or flared portion 6 of the coupling sleeve 5. This anchoring block is tubular, as shown clearly in Fig. 2, and its external surface is tapered, as shown at 14, at an angle corresponding to the angle of the flared portion 6 of the coupling sleeve. An annular groove 15 is formed in the external surface of the anchoring block so as to reduce the contacting surface of the same and thereby minimize the frictional wear. An extended nipple 16 is secured to and rises from the upper end of the anchoring block and this nipple has a reinforced or thickened head 17 at its upper extremity whereby the external and internal shoulders 18 and 19 respectively are formed. Openings 20 are formed through the upper portion of the anchoring block to permit the escape of the fluid into the space within the tubing and around the nipple to pass to the mouth of the well, as will be readily understood.

The plunger 21 of the pump fits snugly within the pump barrel 4 but is free to reciprocate therein and is hollow or tubular to permit the flow of liquid. The upper end of the plunger carries a cage 22 in which is a ball or other form of valve 23 and the upper end of the cage is secured to a spider 24 carried by the lower end of the plunger rod 25. The said plunger rod extends upwardly from the upper end of the pump barrel and through the anchoring block 13 and passes through an opening 26 in the upper end of the nipple 16 so as to be secured to a head block or hammer 27 which is connected to the lower ends of the sucker rods 28.

The operation of the pump will be readily understood. When the parts are in position, as shown in the drawings, the sucker rods are reciprocated and a reciprocating motion thereby imparted directly to the plunger. Upon the down stroke of the plunger, the valve in the cage 12 will be seated and

any fluid which may be within the pump barrel will then be caused to rise through the plunger and on the up stroke of the plunger said fluid will be lifted so as to pass through the openings 20 and thence rise through the tubing, as will be readily understood. On the up stroke of the plunger, a partial vacuum will be formed below the plunger and above the cage 12 so that the valve in said cage will be unseated and an additional charge of liquid will then flow through the shoe and the cage into the pump barrel.

In setting up a pump embodying our improvements, the coupling sleeve 5 is connected to the lowest sections 2 and 3 of the tubing and the tubing is then lowered into the well in the usual manner. The pump is then assembled and connected with the sucker rods and is lowered through the tubing until the anchoring block 13 enters and engages the coupling sleeve 5 which constitutes a seat for said anchoring block. The external diameter of the pump barrel should be such that it will readily pass through the restricted bore of the anchoring block and the springs 8 will, of course, be contracted and lie within the grooves 11 as the shoe passes through said bore. As soon as the shoe emerges from the lower end of the bore, the said springs will expand and bear against the inner wall of the tubing so as to properly position the shoe and the pump barrel and hold the same steady at all times. After the anchoring block reaches the seat or coupling sleeve 5, the walking beam, by which the pump is operated, is adjusted so that the stroke of the same will cause the head or hammer 27 to strike upon the shoulder 18, the head 17 thus serving as an anvil to receive the blows of the hammer and drive the anchoring block to its seat. The repeated blows of the hammer will cause the anchoring block to wedge within its seat so that it will be firmly held thereon by its frictional engagement therewith. After the anchoring block has been fully seated, the walking beam is adjusted so that the stroke of the same will stop the hammer short of the anvil or shoulder 18 and the reciprocation of the sucker rods will then merely effect the usual reciprocation of the pump plunger and will lift the fluid from the well in the ordinary manner.

Should the pump become worn so as to not operate properly, or should some accident happen which renders the pump inoperative, it may be withdrawn without disturbing the tubing so that the necessary repairs may be readily made. To withdraw the pump from the well, the walking beam is adjusted so that its stroke will cause the spider 19 of the head or anvil 17 and this jarring action is repeated until the anchoring block

is loosened upon its seat, whereupon the entire pump may be easily lifted from the well. When the pump is lifted the upper ends of the springs 8 will impinge against the lower beveled surface 7 of the coupling sleeve or seat 5 and will be thereby contracted so that they will readily pass through the bore of said sleeve.

Our device is obviously simple in the construction and arrangement of its parts and may be readily applied to any well tubing at a slight expense. The anchoring block will seat firmly and securely upon the sleeve 5 so that leakage of the fluid which would prevent economical operation of pump will be prevented and, if desired, the annular groove 15 may be fitted with packing so as to still further guard against leakage, but ordinarily we have found the use of such packing unnecessary.

Having thus described the invention, what is claimed as new is:

1. In a deep well pump, the combination with tubing, and a sleeve fitted in the tubing and having an internal conical bore forming a seat, of a pump barrel adapted to pass through said seat, a tapered anchor block secured on the pump barrel and adapted to engage said seat, an anvil connected with and disposed above said anchor block, a plunger mounted within the pump barrel, a plunger rod secured to and rising from the plunger and passing through the anvil, means on the rod above the anvil to impinge upon the anvil and drive the anchor block to its seat, and means on the rod below the anvil to impinge upon the anvil and lift the anchor block from its seat.

2. In a deep well pump, the combination of sectional tubing, a coupling sleeve connecting sections of the tubing and having a contracted bore and flared surfaces above and below said bore, a pump barrel insertible through said bore, an anchor block secured to the upper end of the barrel and adapted to engage the upper flared surface of the coupling sleeve, an anvil connected with and disposed above the upper end of the anchor block, a plunger working in the pump barrel, flexible holding means on the lower end of the barrel constructed to ride on and be compressed by the flared surfaces of the anchor block whereby it may pass through the bore of said block in either direction, and means connected with the plunger to impinge against the anvil and drive the anchor block to its seat or remove it therefrom.

3. In a deep well pump, the combination of tubing sections, a coupling sleeve connecting said sections and having a contracted bore, a pump barrel insertible through said bore, an anchor block secured upon said pump barrel and adapted to seat in the bore of the said sleeve and provided with fluid escape open-

ings in its upper portion, a plunger working in said pump barrel, a plunger rod rising from the plunger, a nipple rising from said anchor block, an anvil across the upper end of the nipple having a central opening through which the plunger rod passes, and devices secured on the plunger rod above and below the anvil to engage the anvil at times and drive the anchor block 10 to its seat or lift it therefrom.

4. In a deep well pump, the combination of sectional tubing, a sleeve connecting sections of the tubing and having flared upper and lower ends, a pump barrel insertible 15 through said sleeve, an anchor block on the pump barrel adapted to seat in the upper

flared end of the sleeve, an anvil disposed above and connected with said anchor block, a plunger within said barrel, a plunger rod rising from the plunger and working 20 through the anchor block and the anvil, a hammer secured on the plunger rod and adapted to impinge against the upper side of the anvil, and a spider carried by the plunger rod above the plunger and adapted 25 to impinge against the under side of the anvil.

In testimony whereof we affix our signatures.
